(57) **CLAIM**

The ornamental design for a pet earmuff, as shown and described.

DESCRIPTION

FIG. 1 is a front, right, top perspective view of a pet earmuff, showing my design.

FIG. 2 is a rear, left, bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right, top perspective view of the pet earmuff of FIG. 1 in a usable state.

The broken lines in the drawings depict portions of the pet earmuff that form no part of the claimed design. The broken lines showing straps and a second earmuff in FIG. 9 depict environmental structure and form no part of the claimed design. All broken lines form no part of the claim.

1 Claim, 9 Drawing Sheets
